UNITED STATES PATENT OFFICE.

PARIS R. FORMAN, OF CHICAGO, ILLINOIS, ASSIGNOR TO NATIONAL PNEUMATIC COMPANY, OF NEW YORK, N. Y., A CORPORATION OF WEST VIRGINIA.

DOOR-OPERATING MECHANISM FOR PASSENGER-CARS.

1,147,854.

Specification of Letters Patent. Patented July 27, 1915.

Application filed November 6, 1912. Serial No. 729,731.

To all whom it may concern:

Be it known that I, PARIS R. FORMAN, a citizen of the United States, residing at Chicago, county of Cook, State of Illinois, have 5 made a certain new and useful Invention in Door-Operating Mechanism for Passenger-Cars, of which the following is a specification.

This invention relates to door operating 10 mechanism for passenger cars.

The object of the invention is to provide a construction and arrangement of door operating mechanism for passenger cars which is simple and efficient.

15 A further object is to provide a construction and arrangement of door operating mechanism wherein a single operating or control handle may serve to operate or control the operation of different doors or of 20 doors on opposite sides of the car.

25 A further object is to provide an arrangement for facilitating the entrance and exit of passengers to and from the car, and whether the entry and exit of the passengers is accomplished on one side or the other of the car.

Other objects of the invention will appear more fully hereinafter.

The invention consists substantially in the 30 construction, combination, location and relative arrangement of parts, all as will be more fully hereinafter set forth, as shown in the drawings, and finally pointed out in the claims.

35 In the drawings,—Figure 1 is a view in floor plan, parts broken off, and parts in horizontal section, showing a portion of a street car and the application thereto of an arrangement of entry and exit way and door 40 operating mechanism therefor, embodying the principles of my invention. Fig. 2 is a top plan view of the control stand, one set of the control arms or rods being omitted. Fig. 3 is a view in elevation, parts broken 45 off and parts in vertical section, of the construction shown in Fig. 2. Fig. 4 is a view similar to Fig. 2 showing another form of door control mechanism and stand embodying the principles of my invention. Fig. 5 50 is a detached detail view in face plan, of the cam device employed in connection with the arrangement shown in Fig. 4.

The same part is designated by the same reference numeral wherever it occurs 55 throughout the several views.

For the purpose of showing a practical

application of a door operating mechanism embodying my invention and an exemplification of an entry and exit way for passenger cars, I have shown a portion of a car 60 with side doorways on opposite sides thereof. As is obvious, these may be at either or both ends of the car or intermediate its ends, as in the case of a center entrance type of car. Where my invention is applied to a 65 car of the center entrance type, the portions at opposite sides of the entrance, indicated at 10, 11, constitute the seating spaces for passengers, and these portions may communicate with the entry and exit platform or 70 landing 13, in any suitable or convenient manner. I shall therefore refer to the platform portion 13, as the landing, and as being distinct from either or both of the seating portions 10, 11. At each side of the 75 landing 13, are three doorways, in the particular form shown in the case of a center entrance car, each doorway having a door. I shall refer to the center door of the three 80 at each side of the landing as the entrance door, and the ones on opposite sides of the center one as the exit door. The doors may be of any suitable or convenient type or construction. I have shown the exit doors 85 as of the swinging type, and the entrance doors as of the folding type, but obviously I am not to be limited or restricted in this respect. Where swinging exit doors are employed, and in the arrangement shown, they are composed of the swinging sections 90 14, 15, 14', 15', 16, 17, 16', 17'; and in the case of the folding entrance doors they are composed of the folding sections 18, 19, 20, 21, 18', 19', 20', 21'. The door sections 14, 14', 17, 17' are respectively carried by vertical shafts 22, 23, 24, 25, located at their outer edges and adjacent the door posts 26, 27, 28, 29. Upon each of said door shafts are crank arms indicated in dotted lines at 30, 31 (see Fig. 1) through which said shafts 95 are rotated to swing the door sections into open or closed position. Similarly, the door sections 15, 15', 16, 16', are carried by vertical shafts respectively, 32, 33, 34, 35 at the outer edges of said door sections which 100 are located adjacent the door posts 36, 37, 38, 39 and each of said shafts is provided with a crank arm indicated at dotted lines 40, 41, through which said shafts and with them the coöperating door sections are rocked 105 into their open or closed position. In like manner the door panels 18, 18', 21, 21' are

carried on vertical shafts 42, 43, 44, 45 having crank arms indicated in dotted lines at 46, 47 for a similar purpose, the panels 19, 19', 20 and 20' folding back upon the panel 5 18, 18', 21, 21' respectively, being suitably guided for this purpose when said door is opened. Of course where sliding or other form of doors are employed in place of the swinging and folding doors shown, other 10 well known and common arrangements may be employed for operating the doors. Similarly, it is immaterial so far as the broadest scope of my invention is concerned whether one or another of the sets of doors constitutes the entrance or the exit doors, or 15 whether the entrance and exit ways are controlled independently by separate doors or not, as it is obvious that the same door or door sections may control both the entrance and exit passages.

Located opposite the entry doorway, and in the preferred arrangement, as shown, is a stand 48, which serves to define a station for the conductor or cashier, and at which station is located means for controlling the doors at the entrance and exit doorways. In practice I prefer to locate this station opposite the entrance doorway and at a point midway the transverse width of the landing 25 or platform, and between the entrance doorways on the opposite sides of the car and approximately midway the communication of the platform or landing with the seating spaces of the car. In the case of a center entrance car, or entrance intermediate the ends of the car, I prefer to locate the conductor's station at approximately the mid point of the landing or platform. By 30 this arrangement entering passengers can distribute themselves on one side or the other of the conductor's station in passing from the entry doorway to the seating space of the car at one end or the other, the said station forming a division barrier for this 35 purpose and by defining a conductor's station at the point indicated not only are passengers able to pass on opposite sides of the conductor's station in entering the car so as to reach the seating space at one end 40 or the other of the car but they also pass by the conductor's station where they pay their fares before entering the seating spaces 45 or portions of the car. This very greatly facilitates the entering movements of passengers and the collection of their fares before entering the seating portions of the car while at the same time permitting distribution 50 of the passengers to the respective ends of the car, thereby securing a desirable distribution of the weight or load of the passengers.

It is obvious that any suitable, convenient or well known means may be located at the conductor's station for facilitating 55 the making of change or deposit of fares

but as these form no part of my present invention further description thereof is unnecessary.

If desired, the landing portion or platform 13 may communicate in any desired 70 manner with the interior or seating portions of the car. In the particular form shown as exemplifying a practical arrangement embodying my invention I have shown bulk-heads between the landing or platform 75 13 and the end portions 10, 11 of the car and comprising or including doorways controlled by doors 49, 50, 51, 52 which, in the form shown, are of the sliding type 80 and designed to slide into pockets 53, 54, 55, 56 in a well known manner, said doors operating transversely of the car, each co-operating pair meeting at a center post 57, 58, when closed. Suitable barriers, indicated at 59, 60 are arranged on opposite 85 sides of the control stand 48, the functions of which are to divide the landing space into separate passageways for entering and alighting passengers, the passageway for entering passengers being directed alongside 90 the control stand whereby the entering passengers are compelled to pass in convenient relation to the control stand to enable the conductor at the control stand to collect their fares before they pass on by and into the seating space of the car. At the same time these barriers afford convenient hand grips for passengers while passing along the passageways, whether entering or leaving 95 the car. The barriers 59, 60, may have 100 any suitable or convenient arrangement and relation. In the particular form shown, and in order to illustrate my invention, the barriers extend from the center landing posts 57, 58, respectively, to the posts 36, 105 38 on one side of the landing which separate the exit from the entrance doorways. Where the opposite side of the landing is used the barriers are turned or reversed so as to extend from the center posts 57, 58, to 110 the door posts 37, 39 on the opposite side of the landing, as indicated in dotted lines in Fig. 1. My invention, however, in its broadest scope, as defined in the claims, is not to be limited to the specific arrangement 115 shown and above described. It is obvious that the doors 49, 50, 51, 52, which separate the landing from the interior of the seating space of the car may be omitted, if desired, in which event the interior seating portions 120 of the car communicate unobstructedly with the landing, with means located on the landing or platform to direct incoming and leaving passengers in different paths or streams so as not to interfere or to block 125 each other.

In the practical operation of a car constructed and arranged as above described, entering passengers, board the car onto the portion 61 of the landing or platform 13, 130

either with or without side steps, indicated at 62, according as the car is of the low or high floor level type. It is also obvious that any suitable or well known type of step, 5 either fixed or foldable, accessible or inaccessible, and operated in any convenient or well known way, may be employed. From this point 61, which is in front of the control stand, or between said stand and the entering doorway, in the particular arrangement shown, the passengers are directed by the barriers 59, 60, past the control stand on their way toward the seating spaces of the car. In the particular arrangement shown 10 15 the passengers have their choice of passing to one side or the other of the control stand through the passages indicated at 63, 64, and thence on through the doorways or passages, 65, 66, into one or the other end or seating portions of the car, as occasion may require. 20 Passengers desiring to alight from the car will be directed from the seating spaces at the opposite sides of the landing or platform 13, through the passages 67, 68, to the exit 25 doorway. Of course it will be understood that when one side of the landing or platform is utilized for boarding and alighting passengers, the doors on the opposite side of the platform are kept closed. It will also 30 be understood that while the conductor's station is at the control stand, ordinarily he will position himself between the control stand and the closed side of the landing or platform, or the side thereof which is not 35 being used as an entering or exit side. At the same time the conductor is permitted a considerable freedom of movement while still remaining within easy reach of the control stand.

40 The doors, where such doors are employed at the sides of the landing may be operated, or the operation thereof controlled in any suitable or convenient manner and by any suitable or convenient construction and arrangement of operating and control devices. 45 I have shown a simple construction and arrangement of devices for this purpose which embodies many advantageous features and which I will now describe.

50 Suitably journaled in the control stand 48, are the vertical shafts 69, 70, 71, upon each of which is secured an operating handle 72, 73, 74, by which said shafts may be rotated. Also mounted upon each shaft, in 55 one form of construction embodying my invention, are two cam plates or members 75, 76, see Fig. 3, each provided with a cam track or groove. In Fig. 2 the cam track or groove of the uppermost plate or member 60 of each shaft is indicated in dotted lines at 77. The cam grooves in the plates 75, 76 are peculiarly shaped. Thus each plate is provided or formed with a groove which is curved concentrically with the axis of the 65 shaft on which the plate is mounted, for a portion of the length of the groove, and is eccentric to the said axis for another portion of its length. Associated with each cam plate is a pivotally mounted lever engaging at one end in the cam groove thereof. Thus, 70 in Fig. 3, a lever 78, is pivotally mounted as at 79, and has its end 80 engaged in the cam groove of plate 75, while another lever 81, pivotally mounted as at 82, has its end 83 engaged in the cam groove of plate 76. The 75 cam plates 75, 76, mounted on the same shaft are so related to each other, and so relatively arranged that when the control handle as 72, thereof, is turned in one direction from a normal or initial position, the engaging end of one of the levers 78, 81 will be engaged by the concentrically curved portion of the cam groove 77, in its associated cam plate or member, and consequently, said lever will be held against rocking movement, while at the same time the end of the other lever will be engaged by the cam portion of the groove in its associated cam plate, and consequently said lever will be rocked. One of the levers 78, 81 is designed 80 to be connected to doors on one side of the landing while the other is designed to be conducted to the corresponding doors on the opposite side of the landing. Thus in the arrangement shown, lever 78, is connected 85 through rods 84, 85, with the crank arms 31, 41, respectively, of door operating shafts 24, 34, while lever 81, is intended to be similarly connected to crank arms on the door operating shafts 23, 33, on the opposite side 90 of the landing. In the same manner the cam plates on each control shaft operate pivoted levers which are respectively connected to corresponding doors on opposite sides of the landing or platform, and said cam plates 95 are so relatively arranged that when the handle of the control shaft is turned in one direction from a control or initial position the door on one side of the landing will be operated while the corresponding door on 100 the other side of the landing will not be operated, and when said control handle is turned in the other direction from its central or initial position, the reverse of this action will take place. Of course it is to be 105 understood that a sufficient range of movement of the control handle on each side of its initial position is permitted to enable the working door to be opened and closed without moving the corresponding door on the 110 opposite side of the landing.

115 From the foregoing description it will be seen that I provide a construction of door operating devices wherein a single control handle controls the operation of doors on 120 opposite sides of the landing but that one of the doors is not operated when the other is in operation.

125 In the construction above described two separate cam plates are mounted on the same 130

control shaft, one concerned in the operation of the doors on one side of the landing and the other concerned in the operation of the corresponding doors on the opposite side of the landing. In some cases I may dispense with one of the cam plates and use only one with each control shaft. Such a construction is shown in Figs. 4 and 5. In this case a single cam plate 86, is mounted on each shaft 69, 70, 71, each cam plate having a cam groove which is curved concentrically with its axis between the points 87, 88, in one direction peripherally thereof, as indicated at 89, Fig. 5, and is cam shaped between said points 87, 88, on the other peripheral direction, as indicated at 90. In this arrangement the ends of both levers 78, 81, engage in the same cam groove, but when the control shaft carrying the cam plate is turned in one direction from an initial position, the engaging end of one of the levers will work in the concentric portion of the cam groove while that of the other lever will work in the cam portion of the cam groove, and when the control shaft is turned in the other direction the reverse of this action takes place, thereby securing identically the same operation as above described with reference to the arrangement shown in Figs. 2 and 3. In this arrangement both doors may be opened, if desired, by the movement of the control handle in the same continuous direction. The doors will be opened consecutively, however, and not in unison, and a reverse movement of the control handle will in like manner close the doors consecutively. Having now set forth the object and nature of my invention and various constructions and arrangements embodying the principles thereof, what I claim as new and useful, and of my own invention, and desire to secure by Letters Patent is,—

1. A car having a landing or platform intermediate its ends arranged to communicate with seating portions at opposite ends thereof, said landing or platform having a door in the side thereof, a stand located on the platform opposite said side door to divide the space opposite said door into separated passages leading respectively to the seating portions of the car and means located at said stand to control the operation of the door.
2. A car having a landing or platform intermediate its ends arranged to communicate with seating portions at the respective ends thereof, said landing or platform having doors in the sides thereof opposite each other, a stand located on the landing or platform opposite and between said side doors to form separated passageways leading respectively to the seating portions of the car, and means located at said stand for controlling the operation of said doors.
3. The combination with a landing or

platform communicating at each end with car seating spaces and having a side doorway and a door for the doorway, of a stand located on the landing or platform opposite said doorway, means located at said stand to control the operation of the door, and barriers located on opposite sides of said stand to divide the space on opposite sides of said stand into separate passages.

4. The combination with a landing or platform communicating at each end with seating portions, and having a door in the side thereof, of a stand located on the landing or platform opposite said door to form separate passages to the respective seating portions of the car, means located at said stand for controlling the door movements, and a barrier located at each side of said stand, and between the same and the adjacent seating portion to divide the space between said stand and seating portion into separate passageways.

5. The combination of a landing or platform communicating at the respective ends thereof with passenger seating portions, and having doorways and doors in the sides thereof opposite each other, a stand located on the landing or platform opposite and between said doorways, means carried thereby to control the operation of the doors, and barriers, located in the spaces between said stand and the passenger seating portions to divide the same into separate passageways.

6. The combination of a landing or platform communicating at the respective ends thereof with passenger seating portions and having doors in the sides thereof, opposite each other, controlling means for said doors located on the landing or platform opposite and between said doors to form separated passages from the side doors to the respective seating portions of the car, and barriers located in the spaces between said doors and the passenger seating portions to divide the same into separate passageways.

7. In a center entrance car, a landing communicating with passenger seating spaces at opposite ends thereof and having a side doorway, a stand located opposite the doorway to divide the landing into separate passages from the side doorway to the respective passenger seating spaces, barriers located in each of said passages to divide the same into separate entrance and exit ways and doors for controlling said entrance and exit ways.

8. In a center entrance car, a landing communicating at its ends with passenger seating spaces, and having a doorway in each side thereof and opposite each other, a stand located on the landing opposite and between said doors to divide the landing into separate passages from each side doorway to the respective passenger seating spaces, barriers for dividing said passages into separate en-

trance and exit ways and doors for controlling said entrance and exit ways.

9. In a center entrance car, a landing communicating at its ends with passenger seating spaces and having a door in the side thereof, means for controlling the operation of said door, said means located on the landing opposite said door to divide the landing into separate passages between the door and the respective seating spaces, and a barrier located in each of said passages to divide the same into separate entrance and exit ways.

10. In a center entrance car, a landing communicating at its ends with passenger seating spaces and having doors in the sides thereof opposite each other, means for controlling the operations of said doors, said means located on the landing opposite and between said doors to divide the landing on each side thereof into separate passageways from said respective doors to the seating spaces respectively, and a barrier to divide each of said passageways into separate entrance and exit ways.

11. The combination with a landing communicating at the ends thereof with passenger seating spaces and having an entrance and an exit doorway in the side thereof, doors for said doorways, a stand located on the landing opposite said entrance doorway to divide the landing into separate passages from said entrance door to the respective seating spaces, a barrier arranged in each of said passages and separating the entrance from the exit doors, and means located at said stand to control the operation of said doors.

12. In the combination with a landing communicating at the ends thereof with passenger seating spaces and having entrance and exit doorways in each side thereof, doors for said doorways, a stand located on the landing opposite and between said entrance doorways to divide the landing into separate passages from said side doorways on each side of the landing to the respective seating spaces, a barrier for said passages and separating the entrance from the exit doors, and means located at the stand for controlling the operation of said doors.

13. The combination with a landing communicating at the ends thereof with passenger seating spaces, and having entrance and exit doors in the side thereof, of means for controlling the operations of said doors, said means located on the landing opposite the entrance door to divide the landing into separate passages from said doors to the respective seating spaces, and a barrier to separate the entrance and exit doors for

each seating space from each other said barriers located in said separated passages to divide the same into separate entrance and exit ways.

14. The combination with a landing communicating at the ends thereof with seating spaces located at opposite ends thereof and having entrance and exit doors opposite each other in the sides thereof, of means for controlling the operation of said doors, said means located on the platform opposite and between said entrance doors, to divide the platform into separate passages from the side doors to the respective seating spaces, and a barrier to divide each of said passages into separate entrance and exit ways, said barriers separating the entrance from the exit doors.

15. A center entrance car having doors arranged opposite each other on opposite sides thereof, a control stand, and means carried thereby for controlling the operation of both doors, the operating means for one door being inoperative when those of the other doors are in action.

16. A center entrance car having a landing portion, doors arranged opposite each other on opposite sides of said landing portion, a control stand located on the platform between said side doorways to form separated passages leading from the side doorways to the respective ends of the car, a shaft journaled in said stand, connections intermediate said shaft and each of said doors for operating said doors, and means whereby when said connections are operative to move one door the connections to the other door are inactive.

17. A car having a landing or platform in the side thereof intermediate its ends, seating spaces at each end of the car at the ends of said landing or platform, said landing or platform having an entrance doorway in the side thereof, and also an exit doorway at each side of said entrance doorway, barriers separating the entrance and exit doorways and forming separated entrance and exit passages, said exit passages leading respectively from the end seating spaces of the car, doors for controlling the entrance and exit doorways, and means located opposite the central or entrance doorway to control said doors.

In testimony whereof I have hereunto set my hand in the presence of the subscribing witnesses, on this first day of November A. D., 1912.

PARIS R. FORMAN.
